TRACY W. DOOLITTLE, CLIFFORD S. WINSOR, AND CHARLES H. VERGASON, OF
BINGHAMTON, NEW YORK.

ADJUSTABLY-MOUNTED SWIVEL-ROLLER.

1,077,906.

Specification of Letters Patent.

Patented Nov. 4, 1913.

Application filed December 9, 1912. Serial No. 735,764.

To all whom it may concern:

Be it known that we, TRACY W. DOOLITTLE, CLIFFORD S. WINSOR, and CHARLES H. VERGASON, respectively citizens of the United States, residing at Binghamton, in the county of Broome and State of New York, have invented certain new and useful Improvements in Adjustably-Mounted Swivel-Rollers; and we do hereby declare

10 the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in adjustable swivel rollers for attachment to door and window openings for loading and unloading lumber, etc., and the object in view is to generally improve upon and render more efficient apparatus of this nature.

25 The invention comprises various details of construction and combinations and arrangements of parts which will be hereinafter fully described, shown in the accompanying drawings and then specifically defined in the 30 appended claim.

Our invention is illustrated in the accompanying drawings, in which:—

Figure 1 is a side elevation showing the device positioned within a door opening and before being fastened to the opposite sides of the opening. Fig. 2 is a view in elevation showing the two bars pivoted together and before being pushed down to horizontal positions. Fig. 3 is a transverse 40 sectional view through the jambs of doors and showing in top plan view the bars held in engagement with the jambs of the door, and Fig. 4 is an enlarged view, partially in section and partially in elevation, through 45 the bars and the means for holding the swivel yoke upon which the roller is mounted.

Reference now being had to the details of the drawings by letter, A and B designate 50 two bars, preferably of metal and angular in cross section and which are provided with a series of perforations C through which a pivotal pin D' may be passed to form a hinged connection between the two bars.

55 One of the bars is provided with a hook C'

projecting from the upper edge thereof and adapted to engage over the upper edge of the other bar when the two are adjusted in horizontal positions. By the provision of the hook C', which is carried by the bar A and hooks over the upper edge of the bar B when the two bars are in the positions shown in Fig. 1, further downward movements of the bars will be prevented, while the springs D at the ends of the bars will securely bite 60 into the jambs of the door way and form means for supporting the bars. Springs D are fastened to the outer end of each bar and which springs are preferably curved with bluntly sharpened edges adapted to friction- 65 ally engage the side of the door or window opening in which the bars are to be held and serve to insure a rigid engagement with the jambs or frame, when a leverage is applied to the bars, bringing the same to horizontal 70 positions. One of said bars is provided with an aperture E formed in the horizontally disposed portion thereof and which is adapted for the reception of the bolt F' which passes through the bearing member F, which latter has a recessed head F² in which the swiveled bearing member F³ is seated and which carries the yoke H, in the arms of which the pintles 1 of the rollers 1' are journaled. A hand wheel K is provided with a 80 hub portion, interiorly threaded and is adapted to bear against the under surface of the angle bar A, forming a means co-operating with the swiveled member F³ to hold the yoke H in an adjusted position by friction. 85

90 By the provision of an apparatus as shown and described, it will be noted that the bars may be adjusted and securely held to the sides of door or window openings of various widths. The roller being swiveled would 95 permit the lumber or other objects resting thereon to be passed through the opening at different angles thereto.

What we claim to be new is:—

An adjustable swivel roller for loading 100 and unloading lumber through door and window openings comprising two bars adjustably pivoted together, a hinge fixed to one bar and adapted to engage over the top of the other to hold the bars with their opposite edges flush with each other, springs fastened to the ends of the bars and having laterally extending portions which are curved, the ends of the springs adapted to friction- 105 ally engage the edges of the openings in 110

which the apparatus is held, one of said bars having an opening, a swiveled bearing member having a shank portion resting upon the apertured bar and provided with a central aperture registering with said opening, the upper portion of said swiveled member having a recess with a tapering wall, a bracket member, a roller carried thereby, a pin passing through said bracket member and 10 swiveled bearing and the opening in said bar, the end of said pin being threaded, and a wheel fitted to said threaded end and

adapted to bear against the under surface of the bar, as set forth.

In testimony whereof we hereunto affix 15 our signatures in the presence of two witnesses.

TRACY W. DOOLITTLE.
CLIFFORD S. WINSOR.
CHARLES H. VERGASON.
